UNITED STATES PATENT OFFICE

128,420

DESIGN FOR A TRANSPARENT OVERSHOE OR SIMILAR ARTICLE

Addeline J. McGillicuddy, New York, N. Y.

Application June 26, 1941, Serial No. 101,689

Term of patent 3½ years

To all whom it may concern:

Be it known that I, Addeline J. McGillicuddy, a citizen of the United States of America, residing in New York city, county of New York, and State of New York, have invented a new, original, and ornamental Design for a Transparent Overshoe or Similar Article, of which the following is a specification, reference being had to the accompanying drawing, forming part thereof.

The figure on the drawing is a perspective view of a transparent overshoe or similar article showing my new design, the opposite side presenting substantially the same appearance as the side shown.

I claim:

The ornamental design for a transparent overshoe or similar article, substantially as shown and described.

ADDELINE J. McGILLICUDDY.
